Inventor,
Daniel R. Pratt.

United States Patent Office.

DANIEL R. PRATT, OF WORCESTER, MASSACHUSETTS, ASSIGNOR TO J. MARCUS RICE, OF THE SAME PLACE.

Letters Patent No. 61,864, dated February 5, 1867.

IMPROVEMENT IN SPIKE MACHINES.

The Schedule referred to in these Letters Patent and making part of the same.

TO ALL WHOM IT MAY CONCERN:

Be it known that I, DANIEL R. PRATT, of Worcester, in the county of Worcester, in the State of Massachusetts, have invented a new and improved mode of forming Heads upon bars of metal by means of a revolving or rotating machine; and I do hereby declare that the following is a full and exact description thereof, reference being had to the accompanying drawings and to the letters of reference marked thereon.

The nature of my invention consists in the arrangement of disks or flange-face plates on two revolving or rotating shafts, and on the upper one, as seen in Figures II and III, is placed a pocket to receive the heading dies for forming the upper portion of the head to be made on the blank or bar, and on the lower shaft is placed a disk or face plate, with pockets for the dies which are placed on the disk of a revolving wheel obliquely across the radial line of the wheel, as seen in Fig. III, to hold the bar or blank to be headed in the dies on an oblique line across the radial line of the wheel.

To enable others skilled in the art to make and use my invention, I will proceed to describe its construction and operation.

I make a machine with two shafts, geared together so as to revolve in opposite directions, with two gears, as seen in Fig. II, or the two end gears may be dispensed with by using the driving gears in the middle of the frame, and thereby make both ends of the shafts to receive the heading arrangement, and then I place on the shafts the disks or wheels with their pockets to receive the heading and holding dies. The pockets on the disk of the lower shaft are made tapering on the inside to conform to the shape of the dies, with a shoulder to receive the pressure of the heading dies to keep them from being forced through the pockets in forming the head on the blanks. The holding dies are made tapering on the outside to conform to the pockets, so as to produce a squeezing grip on the blank while being headed, which has a shoulder on it to rest on that of the pockets after being forced to it by closing the die tightly on the bar or blank by means of the two tapering surfaces of the pockets and holding dies, as seen in Fig. III. The holding dies are divided and hinged, and provided with handles, as seen in detached view, letter B. The shape of the lower portion of the head to be made is formed in the top of the holding dies, and when put into the pockets it will be seen that it is held on an angle obliquely across the radial line of the wheel or disk while in the die to be headed, which is very important in producing heads on bars of metal by the means of two revolving wheels or rolls, so that when the end of the blank comes in contact with the heading die the pressure of the latter will be in a line coincident with the axis of the blank so as to stave it up or upset it, until the die is completely filled before the head is formed. Different holding dies, of varying obliquity, may be used to vary the position of the blank, if desired.

What I claim as my invention, and desire to secure by Letters Patent, is—

1. The divided holding die B, hinged together and made with handles, and of tapering shape from top to bottom, with a shoulder on the outer surface.
2. In combination with the holding die B, I claim a revolving pocket made fast to one of the revolving wheels, with a corresponding tapering surface on the inside, and a shoulder to receive the pressure of the heading die while the head is being formed on the bar of metal.
3. In machines for heading bars of metals in which rolls are used, substantially as herein described, I claim placing the blank at such an angle in the die that when the end of the blank or bar comes in contact with the heading die the pressure will be in a line coincident with the axis of the blank, or nearly so, as set forth.

DANIEL R. PRATT.
